[57] CLAIM

The ornamental design for tray assembly for combined copying machine, printer and facsimile transmitter-receiver, as shown and described.

DESCRIPTION

FIG. 1 is a top, front, and left side perspective view of a tray assembly for combined copying machine, printer and facsimile transmitter-receiver showing our new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof; and,

FIG. 8 is a front, top and left side perspective view thereof, the broken line showing of a combined copying machine, printer and facsimile transmitter-receiver is environmental only and forms no part of the claimed design.

FIG. 1

FIG. 2

FIG. 3
